UNITED STATES PATENT OFFICE.

JOHN M. BASS, OF JOPLIN, MISSOURI.

HOISTING DRUM.

Application filed August 10, 1925. Serial No. 49,369.

To all whom it may concern:

Be it known that I, JOHN M. BASS, a citizen of the United States, residing at Joplin, in the county of Jasper and State of Missouri, have invented new and useful Improvements in Hoisting Drums, of which the following is a specification.

My present invention has reference to a hoisting drum and has for its objects to provide a hoisting drum with opened or apertured heads, whereby a free circulation of air may be introduced therethrough and wherein the said drum is provided with an interchangeable friction member or face so that the necessity of destroying a drum when the friction surface or face thereof has become worn will be effectively overcome.

A further object is the provision of a drum for this purpose in which a friction cone, surface or face has an interengagement with the inner face of one of the hollow heads of the drum and is provided with simple means for removably locking the said element on the said face of the drum.

With the above broadly stated objects in view and others which will appear as the nature of the invention is better understood, reference is to be had to the drawings, which accompany and form part of this application.

In the drawings:—

Figure 1 is a side elevation of the improvement.

Figure 2 is an end view thereof.

Figure 3 is a sectional view approximately on the line 3—3 of Figure 2.

Figure 4 is an end view of the drum with the friction member removed.

Figure 5 is an inner face view of the friction member.

Figure 6 is an end view of the drum opposite that disclosed by Figure 2.

The hollow cylindrical body of the drum is indicated by the numeral 1. One of the fixed heads thereof is in the nature of a winged flange 2 and is connected to the drum body by spokes 3. By reference to the drawings, it will be noted that the spokes project beyond the periphery of the body 1 so as to provide air openings between the head and body. The spokes 3 are of course centrally connected to a hub 4.

The second fixed head 5 of the drum has an outwardly directed peripheral flange 6 for a brake band. The outer face of the

head 5 has an annular depression 7 and is formed with inner notches 8 that communicate with the depression 7. From the hub 9 of the drum head 5 there radiate lugs or enlargements 10 that terminate with the inner walls of the respective notches 8. The side walls provided by the notches 8 are disposed at outward angles with respect to each other, and the inner walls of these notches are formed with openings which align with similar openings in the spokes 3 of the head 2.

In the ordinary type of winding drums no provision is made for the free circulation of air therethrough or for the circulation of air through the cable wound on the drum. Therefore, in addition to the spaces between the spokes 3, and the interior and exterior of the drum body 1, I provide the head 5, inward of its flange 6, with openings 11. In this manner it will be noted that a free circulation of air is directed into the drum and to the exterior thereof so that an overheating of the drum by the cable which is wound thereon, or from other causes will be to a great extent obviated. The air circulation is, of course, also directed onto the cable. Also with this class of drums the friction element for the clutch is integrally formed with the head thereof, similar to the flanged head 5, as the frictional clutch surface is subjected to great strain and the same is liable to breakage and a broken clutch surface renders the entire drum useless. Therefore, in carrying out my invention I provide a removable clutch or friction surface. In the showing of the drawings the clutch or friction surface or element is in the nature of a clutch ring 12. The ring 12 has on its inner end inwardly projecting wedge-shaped lugs 13 that are designed to be received in the wedge-shaped notches 8. There is passed through the lugs 13 and through the referred to openings in the head 5 and the spokes 3 of the drum the shanks of headed rods 14, and screwed on the outer ends of these rods there are nuts 15. By such arrangement it will be noted that should injury be inflicted to a clutch ring 12 the same may be easily removed and replaced by an undamaged ring.

The simplicity and advantages of my construction will, it is thought, be perfectly apparent to those skilled in the art to which such invention relates, when the foregoing

description is read in connection with the accompanying drawings.

Having described the invention, I claim:

1. A drum of the class described comprising a hollow body having heads on the ends thereof, one of said heads being flanged outwardly, the second head comprising a ring member, spokes connecting the ring member to the body and said spokes merging into a hub, the outer face of the second head having an annular depression, and wedge-shaped notches communicating with the depression, a ring clutch member received in the annular depression and having wedge lugs received in the notches and means passing through the lugs, the said head and the spokes of the second head for removably securing the clutch ring on the drum.
2. A winding drum having a hollow body, heads formed on the ends thereof, one of

said heads being apertured and provided with a peripheral rim, said head having an annular depression on its outer face, wedge-shaped notches communicating with the depressions, lugs on the said face of the head inward of the notches, a friction ring received in the depressions and having wedge lugs to be received in the notches, the second head being in the nature of a ring member which is disposed outwardly with respect to the body, spokes integrally formed with the ring member and the body and merging into a hub and securing means passing through the lugs of the friction ring for the first mentioned head and the spokes of the last mentioned head for holding the friction ring on the drum.

In testimony whereof I affix my signature.

JOHN M. BASS.
